HARNESS
TRIMMING

CHARLES M. THEBERATH
JACOB H. THEBERATH
New Design for Harness Trimmings.

No. 3255

PATENTED
NOV 17 1868

Inventor:

Charles M. Theberath
Jacob H. Theberath

United States Patent Office.

CHARLES M. THEBERATH AND JACOB H. THEBERATH, OF NEWARK, NEW JERSEY.

Design No. 3,255, dated November 17, 1868.

DESIGN FOR HARNESS-TRIMMINGS.

The Schedule referred to in these Letters Patent and making part of the same.

To all whom it may concern:

Be it known that we, CHARLES M. THEBERATH and JACOB H. THEBERATH, of the city of Newark, county of Essex, State of New Jersey, have produced a new Design for Harness-Trimmings, of which the following is a full and clear description, reference being had to the accompanying drawings, making part of this specification.

The nine figures on the drawing represent the different pieces of a set of harness-trimmings, which are all designed so as to strictly conform with each other, and in which the buckle-shape is introduced and maintained as the principal and novel feature of each single part of the set.

Figure I is a fly-hook.

Figure II is a terret.

Figure III is a trace-buckle.

Figure IV is a fly-terret.
Figure V is a breeching-ring.
Figure VI is a gag-runner.
Figure VII is a martingale-ring.
Figure VIII is a tug-buckle.
Figure IX is a bolt-hook.

Claim.

What we claim as our invention, and desire to secure by Letters Patent, is—

The new design for harness-trimmings, or the different parts thereof, as herein set forth.

CHAS. M. THEBERATH.
JACOB H. THEBERATH.
